UNITED STATES PATENT OFFICE.

WILLIAM SNEE, OF WEST ELIZABETH, PENNSYLVANIA, ASSIGNOR TO
JOHN A. SNEE, OF WEST ELIZABETH, PENNSYLVANIA.

WAVE-PROPELLED MOTOR.

No. 839,328.

Specification of Letters Patent.

Patented Dec. 25, 1906.

Application filed April 3, 1906. Serial No. 309,633.

To all whom it may concern:

Be it known that I, WILLIAM SNEE, a citizen of the United States, residing at West Elizabeth, in the county of Allegheny and State of Pennsylvania, have invented certain new and useful Improvements in Wave-Propelled Motors; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to an improved wave-propelled motor; and it comprises, in addition to a suitably-constructed frame, a series of vertically-arranged deflecting-blades arranged at regular intervals about a circle, each of said blades being tangent to an inscribed circle, a rotatable wheel arranged within the circle of the deflecting-blades, said wheel having a plurality of propeller-blades with intervening space between each pair, each of said pair forming an obtuse angle the one with the other; and the invention further consists in the certain details of construction and combination of parts, as will be fully described hereinafter.

In the accompanying drawings, Figure 1 is a central side sectional elevation of my improved wave-propelled motor, the same being constructed and arranged in accordance with my invention. Fig. 2 is a sectional plan view of the same, said section being taken on the line $x-x$ of Fig. 1. Fig. 3 is a side elevation of the bed-plate, showing a portion of the standards which support the top plate.

To construct a wave-motor and adapt the same for use in the ocean, lakes, or rivers having a pronounced current, I first put in place a suitable foundation 1, upon which is secured by bolts 3 a bed-plate 2. This bed-plate comprises a flat rectangular casting having at its center a socket 6 for the reception of the lower end of a vertically-arranged shaft 7 and is also provided with a series of upwardly-projecting flanges 2', to which vertical deflecting-blades are attached. This shaft 7 is provided with a collar 9 and is arranged in a ball-bearing at the base, said bearing consisting of a sleeve-cap 8, resting upon a series of balls arranged in a groove formed on the top of a boss 5, cast integral

with the bed-plate 2, which engages with the above-mentioned cap 8 to exclude sand or dirt from the bearing, as will be best seen at Fig. 1 of the drawings.

Resting upon the top of the cap 8 is an annular plate or wheel 11, which is made rigid with the shaft 7 and said cap by means of a key 13. Above this lower wheel 11 is another, similar in form, also made rigid with the shaft 7 by a key passing through the hub and shaft. Arranged in radial relation to these two wheels 11 are a series of propeller-blades 12, which are equidistant the one from the other and occupy a perpendicular position. Attached to these same wheels 11, external of the propeller-blades 12, is a second series of propeller-blades 18, which are arranged at regular intervals and in lines tangent to an inscribed circle. These two sets of propeller-blades 12 and 18 are separated the one from the other, leaving an intervening space, and each pair in radial relation form an obtuse angle, as will be seen by reference to Fig. 2 of the drawings.

Attached to the bed-plate 2 are a suitable number of standards 4, which serve to support a top plate 14, said plate being formed with annular concentric flanges on the under side and is provided with a hub 15 at the center, said hub being fitted with a bushing or brass 16, which serves as a bearing for the reduced upper end of the shaft 7.

Attached to the bed-plate 2 and to the plate 14 above are a series of deflecting-blades 17, placed at regular intervals about a circle, said blades being of flat metal, slightly dished or curved in cross-section and arranged similar to those, 18, of the propeller—that is, approximately tangent to an inscribed circle. These deflecting-blades 17 are one-half in number of those of the propeller, but may be increased or diminished, if desired. The inner edges of these deflecting-blades 17 are slightly removed from those, 18, of the propeller in such manner that the latter may be free to revolve.

In operation the apparatus may be partly or altogether submerged in the water. The waves or current of water entering the wide openings between the deflecting-blades 17 are directed against the radial blades at approximately right angles to the same, and the force of said waves are more or less directed against one-half of said propellers by

passing through the space between. It will be noticed that by this construction and arrangement of deflectors the waves or current entering from any direction will rotate the motor in but one direction.

Various slight modifications and changes may be made in the details of construction without departing from the spirit of the invention. Therefore I do not wish to confine myself to the exact construction shown and described, but wish to claim all such modified forms as would come properly within the general scope of the invention.

Having thus described my invention, what I claim, and desire to secure by Letters Patent, is—

1. A motor of the class described, comprising an inner rotatable wheel having a series of radially-disposed propeller-blades and a

series of deflecting-blades forming an obtuse angle, the one with the other and leaving an intervening space, in combination with a series of deflecting stationary blades, arranged tangent to an inscribed circle, as described.

2. A motor of the class described, comprising an inner rotatable wheel having a series of radially-disposed propeller-blades and a series of deflecting-blades with intervening space, in combination with a series of deflecting-stationary blades arranged tangent to an inscribed circle, said blades being dished or curved in cross-section, as described.

In testimony whereof I affix my signature in presence of two witnesses.

WILLIAM SNEE.
